UNITED STATES PATENT OFFICE

WILLIAM CHARLES WALLACE, OF KANSAS CITY, MISSOURI

HYDRO-SPORTING MACHINE

Application filed January 21, 1928. Serial No. 248,464.

This invention relates to a submersible sporting vessel, which I term a hydro-sporting machine, designed especially for the use of bathers at bathing beaches and the like.

- 5 The object of my invention is to provide a vessel in which the bather may sit and propel him or herself over the surface of the water, and dive to a greater or less extent beneath the surface of the water.
- 10 A further object is to provide a buoyant vessel which is unsinkable and uncapsizable, and which will afford exercise, amusement and enjoyment with complete safety.

The invention consists of the features of 15 construction, combination and arrangement of parts, hereinafter fully described and claimed, reference being made to the accompanying drawings, in which:—

Figure 1 is a side elevation of the vessel.

20 Figure 2 is a longitudinal section on line A—A of Figure 3.

Figure 3 is a top plan view of the vessel.

Figure 4 is a transverse section on line B—B of Figure 1.

25 In carrying my invention into practice I provide a submersible boat comprising a body or hull 1, which may be of any suitable form, preferably of the form as shown. This boat body is preferably constructed of sheet metal 30 throughout, but may be made of any other suitable material or materials.

The front and rear or bow and stern ends of the body 1, are separated in a manner to form a central portion thereof by vertical 35 transverse partitions 2 and 3, and being open at the bottom allowing the water to be in the center portion thereof, thus the bather is sitting in water at all times. The bow and stern ends are rendered buoyant by means of water-tight tanks 4 and 5 arranged in a manner and size to cause the body 1, to float partly submerged to a depth indicated by the water line when loaded. The center of gravity and buoyancy are so arranged as to prevent 45 any liability of the craft capsizing under ordinary conditions of service.

The central portion of the body 1 is formed to provide a well or cockpit 6 the side walls of this well or cockpit are cut away as shown 50 at 7. The well or cockpit 6 is also open at its

bottom shown at 8 to allow the water to normally rise therein to the water line level, giving the occupant the benefit of flow of water.

The boat as shown is designed to receive a single occupant, though may be made to carry two or more occupants, who sit within the cockpit 1, with the lower portion of his or her body submerged in the water and manually propels the boat by means of suitable propelling mechanism hereinafter described. A water proof seat or saddle 9 for use of the occupant is shown and carried by a post 10 fitted for longitudinal and vertical adjustment 11, clamping nuts 12 or the like being provided for securing the seat in the desired position. The bather occupying the seat 9 propels the craft through the medium of pedal cranks 13 carried by a crank shaft 14 journaled in bearings upon hanger brackets 15, to which shaft is fixed a spiral gear 16 meshing with a spiral worm pinion 17 upon the forward end of a longitudinal shaft 18. The brackets 15 depend beneath the well or cockpit 6 and held laterally by diagonal braces 19, suitably fixed to the hull, the shaft 18 also being provided with bearings carrying a screw propeller 20 a U-shaped guard or shield 21 secured to the hanger brackets 15, which guard encloses the drive gearing and prevents the clothes or limbs of the occupant from coming in contact therewith and becoming damaged or injured. It will be understood that the lower portion of the body of the operator will be submerged and that by application of foot power to the drive gearing described the propeller will be operated to drive the craft forward.

Fixed to the sides of the stern end of the body 1 are stationary water-tight tanks 22 which act as stabilizers to normally maintain the horizontal trim and stability of the craft. Arranged at the sides of the bow portion of the body 1 are diving planes 23 which are normally disposed in a horizontal plane and operate in conjunction with the tanks 22 keeping the vessel longitudinally and laterally balanced. The said planes 23 are mounted upon the opposite ends of a transverse shaft 24 extending through the

body 1 and provided with a rocker arm 25. By the tilting of the planes 23 the bow of the craft, may be directed downwardly for diving and upwardly for rising actions. A rudder 26 is provided at the stern for steering the vessel laterally, the post of this rudder is provided with the usual rudder quadrant 27 connected to the control cord, wire or wire rope 28 passing along the sides of the body 1 through guide pulleys 29 and 30 and having its intermediate portion wound a number of times around a drum 31. The drum 31 is journaled for rotation at 32 and held from longitudinal movement in a bracket 33 supported by the forward end of the body 1, and extended through said drum is a control shaft 34 provided with a hand wheel 35. The hand wheel 35 is arranged so as to be conveniently grasped and manipulated by the operator, and the shaft 34 is splined or feathered to slide longitudinally independent of the drum 31 and to connect the drum therewith for rotation in either direction, whereby the rudder 26 may be adjusted for steering the vessel. Fixed to the shaft 34 is an annularly grooved collar 36 engaged by the forked or upper end 37 of the rocker arm 25, whereby, through forward and backward sliding movements of the shaft 34, the planes 23 may be tilted for diving and ascending actions, as will be readily understood.

The craft is particularly intended for use by bathers at bathing beaches, for the purpose of aquatic sport, exercise and amusement, and it will be understood that the bather may propel the craft about the surface of the water at will, and may also, by tilting the planes 23, dive to a greater or less extent beneath the surface of the water. As the operator drives the pedals, the craft will move forward on an even keel until the planes 23 are tilted. She then goes down at the bow to an extent determined by the angle of inclination and the speed of the craft. The moment the operator slackens speed or stops pedaling, the craft comes back to its normal position at even keel, as the buoyancy is sufficiently great to keep the craft afloat at all times, except when she is forced under by the planes. A type of sport machine embodying the hydroplane diving principle, is thus provided which offers every desired element of absolute safety, sport, exercise and amusement.

Having thus fully described my invention, I claim:

1. A submersible hydro-sport boat comprising a hull having a central bottomless cockpit, said hull enclosing bow and stern air tanks, lateral stabilizing air tanks spaced from after part of said hull on each side thereof, and manual propelling means for said boat.

2. A sport boat as in claim 1 wherein the

cockpit is provided with a vertically and horizontally adjustable seat.

3. A sport boat as in claim 1 where the hull is provided with diving planes and a steering rudder and a single operating control common to both said diving planes and steering rudder.

WM. C. WALLACE.
